MEANS FOR SHORTENING THE EFFECTIVE LENGTH OF LINES OR CORDS

John Waldheim, Elizabeth, N. J.

Application December 5, 1938, Serial No. 243,956

19 Claims. (Cl. 211—119.09)

This invention relates to means for pulling on a line or cord to tighten it. Embodiments of the invention may be employed for purposes such as tightening clothes lines, tent lines, and guy lines.

The tendency of the line when tightened is to cause the device to rotate in a reverse direction which would slacken the line. This is prevented, however, by suitable holding means which forms part of the device.

In one form of the invention the device may be used on a stationary clothes line or on a pulley clothes line. In the latter case it may be demountably attached to the clothes carrying reach of the line and travels therewith.

In each of two other forms of the invention the device serves not only as a tightener but also as a means to prevent spreading of the various reaches of the pulley line when the latter is loaded with articles of clothes.

Other features and advantages will hereinafter appear.

In the drawings which form part of the specification:

Fig. 1 is a side elevation of a two-reach clothes line showing the invention applied thereto;

Fig. 1a is a side elevation of a four-reach clothes line with another form of the invention applied thereto;

Figs. 2 and 3 are an edge view and a side view respectively, of one form of the device showing it applied to a line preparatory to a tightening operation;

Figs. 4 and 5 are views similar to Figs. 2 and 3 showing the device rotated through 180 degrees during the line tightening operation;

Fig. 6 is a side elevation of a combined tightener and holder in which the handle member is provided with a roller to run on the upper reach of a two-reach pulley clothes line;

Fig. 7 is a front elevation of a modification of the form of invention shown in Fig. 6 and illustrates a combined holder and tightener for use on pulley clothes line having more than two reaches;

Fig. 8 is a side elevation as seen from the right hand side of Fig. 7; and

Fig. 9 is a sectional top plan view taken on the line 9—9 of Fig. 7.

Similar reference characters represent similar parts throughout the specification.

The form of device or tightener 29 illustrated in Figs. 1 and 2 to 5, inclusive, comprises an arm or body part 30 having at one end a winding means 31 including a reel 32. A slot or space 33

divides the reel 32 into two members 34 and 35. The reel also includes two notches 37 and 39.

The tightener 29 is detachably connectable to the lower reach 40 of a pulley clothes line 41, Fig. 1. The clothes line also includes an upper reach 40', the two reaches forming an elongated loop supported at opposite ends by suitable pulleys.

To attach the tightener 29 to the line reach 40 it is placed as in Figs. 2 and 3 with the reach 40 in the slot 33. The tightener is subsequently rotated sidewise in the direction of the arrow in Fig. 2 so that the members 34 and 35 grip the line 40. As the rotation of the tightener continues the line portion 40 enters the notches 37 and 39 and winds around the reel 32 which forms a base for the members 34 and 35. In the event that the line is not sufficiently tight when the device has been rotated through 270 degrees the latter may be rotated still further until the line is sufficiently tight. Due to the taut condition of the line it tends to reversely rotate the tightener 29. This is prevented, however, by suitable holding means 45 caused to engage the line.

The tightener 29 may be composed of wood or any other suitable material. When, however, a kind of wood is used which is not of great strength, the members 34 and 35 may be reinforced, against breakage at the base 44, by screws 44x, Fig. 3.

The holding means comprises two grooves 46 formed in opposite faces of an extension 47 on the body part 30 into either one of which a portion of the line may be inserted. A tongue 48 projects from the extension 47 towards the reel winding device 31 and assists in keeping the line in the grooves 46. To insert the line into the groove the tightener is rotated until the extension is slightly past the reach 40 so that the said reach may be moved past said tongue towards the body part and then into alignment with the slot 46. The tightening device is then permitted to reversely rotate slightly until the line reach has entered said groove 46. If the tongue 48 is made long enough it may serve alone, without the grooves 46, to hold the reach 40 on the extension 47 since it forms, with the body part or handle 30, a slot extending towards and having its open end nearest the reel 31 so that the reach 40 may readily be placed into said slot. When, however, the grooves 46 are used with the tongue 48 it may be shorter depending upon the depth of the grooves 47.

Since the tendency of the line 40 is to reversely rotate the tightening device 29 the line must be inserted into the groove in the face of the device

opposite to that at which the line portion leaves the winding means 31. Thus the tendency of the line to reversely rotate the tightening device 29 causes the extension 47 thereof to be pressed tightly against the reach 40 and prevent accidental removal of said reach from the groove 46. It will also be understood that the end of the body part 30 which has the extension 47 serves as a lever arm by which the rotation of the winding means 31 is facilitated. It will also be understood that the members 34, 35 and the post 44, Fig. 3, form a cleat which constitutes the winding device 31.

By employment of the tightener 29 the usual slip knot 40a and the surplus length of line, Fig. 1, which is put up in loops 40b on the line may be left undisturbed during a line tightening or slackening operation, or the slip knot 40a and surplus line portion 40b may be entirely eliminated, in which event the two ends of the line would be directly secured to each other. Although only one tightener 29 is shown on the pulley line 41, it should be understood that more than one may be used if desired. For example, a tightener may be put on the line prior to hanging clothes thereon and if the lower reach 40 sags too much after some of the clothes have been put thereon another tightener 29 may be put on the reach 40 to take up the sag produced by the weight of the clothes. This may be repeated as often as it is found necessary.

The form of tightener 29r shown in Figs. 7 to 9 is composed of two major components, namely, a horizontal component or member 80 and a vertical component or member 81. The member 80 includes the winding means 31r and the holding means 45r. The vertical member which is an arm or lever serves as means by which the tightener may be operated to rotate the winding device 31r to wind up a portion of the line thereon. The members 80 and 81 are held together by a wood screw 82. To prevent turning of the members 80 and 81 with respect to each other they are interlocked. For this purpose the member 80 is provided with a slot 83, Fig. 9, and the member 81 with a slot 84, Fig. 8, each member fitting into the bottom of the slot of the other member.

After a portion of the line is wound on the reel 31r of the tightener 29r the holding means 45r is placed under the line portion 412 as in Fig. 7, so that said line portion engages in the groove 46r and behind the tongue 48r. It will be understood that the member 81 may hang down from the line portion 40, as shown in broken lines in Fig. 1a and may be comparatively long to facilitate rotation of the tightener during a line winding operation. The member 80, however, is comparatively short to occupy a minimum space between the articles of clothes on the line.

When the line portion 412 is to be unwound from the tightener 29r, to loosen the line, the holding means is first moved from engagement with said line position and the tightener is in the position shown in broken lines in Fig. 1a with the long arm 81 extending from the line so that the tightener may be permitted to rotate, under the influence of the tension or taut condition of the line, about an axis which is parallel to the vertical member 81. During the winding of the line portion, however, the tightener is rotated about the axis of the reel 31r, which extends at right angles to the vertical portion or arm 81. The end 85 of the member 81 is shaped so as to facili-

tate the passage of the line portion over it during the unwinding operation of the line.

The tightener 29 may be rotated in a direction reverse to the winding direction and is likely to rotate rapidly during an unwinding operation. This is caused by the weight of the clothes on the line and may result in the tightener striking the hand if it gets out of control of the operator. Such a possibility is prevented, however, when the tightener 29r rotates freely to unwind the line, while the handle 81 extends vertically downward from the line, as indicated in broken lines toward the right in Fig. 1a. In this position the handle 81 may be guided by both hands of the operator to permit the tightener to rotate about an axis which is substantially at right angles to the winding axis and substantially parallel to the handle 81.

The vertical member 81 extends upwardly from the member 80 and is provided with a roller 86t which runs on a spindle 87t and travels on the reaches 41x and 41y of the clothes line 41v, Fig. 1a, to hold said reaches and lower reach of the clothes line close to each other.

It should be understood that the winding device 31r and the holding means 45r in addition to performing their individual functions also cooperate to assist in holding the member 81 in an upright position in a plane extending transversely of the line.

The roller 86t is located in a vertical slot 86x and a diagonally disposed slot 92 communicates therewith, through which the reaches 41x and 41y may be passed to the reach accommodating slot 86x in which the roller 86 is located. To do this, however, it is necessary to swing or tilt the upper end of the device 29r laterally, rightwardly in Fig. 1, until the slot 92 is substantially parallel with the reaches 41x, 41y so that they may be passed freely through the slot. This is also done when it is desired to remove the reaches from the device 29r. It will be understood that the diagonal arrangement of the slot 86y prevents accidental detachment of the device 29s from the reaches 41x and 41y.

The holder 29r comprises a horizontal member 80 and a vertical member or body part 81. The member 80 is composed of a winding means 31r and holding means 45r. This form of device is constructed for use on a clothes line 41v having four reaches 41w, 41x, 41y, and 41z, Figs. 1a and 7. The reaches 41x and 41y are intermediate reaches and they travel in the same direction, the reach 41x extending from pulley 48c, Fig. 1a, to a pulley 48z, and the reach 41y extending from a pulley 48e to a pulley 48j. The outer reaches 41w and 41z also travel in the same direction but opposite to the direction of travel of the reaches 41x and 41y. This type of clothes line is disclosed and claimed in my application, Ser. No. 243,955, filed December 5, 1938, now Patent #2,292,415, dated August 11, 1942.

The upper end of the device or holder 29r includes a hook-like portion 88 which extends over the upper reach 41w of the clothes line to keep the reach 41w properly spaced with respect to the other reaches. Two guards 89 and 90y are provided to prevent accidental detachment of the device 29r from the upper reach 41w. The guards are formed by a diagonally extending slot 91 through which the reach 41w is passed to a position under the hook 88. To do this, however, the holder is tilted to bring slot 91 substantially parallel to the reach 41w of the line

so that said reach may be passed freely through the slot 91 and under the hook 88 or be removed from under it. When the body part is in a vertical position the guards 89 and 90 are so related that it is impossible for the reach to pass out through the slot 91.

A roller 93 is also provided in the slot 86x which may ride on the reaches 41x and 41y in case the device 29r becomes inverted by the articles of clothes when they are wrapped around the line 10 by the wind.

It should be understood that the vertical component 81 may reach an upwardly extending position, as at the left of Fig. 1a, when the line is sufficiently tight and the reach 41z has been placed in the holding means 45r. It is then merely necessary to tilt the device, upper end rightwardly in Fig. 1a, so that the upper reach 41w may be inserted through the slot 91 and that the intermediate reaches 41x and 41y may be inserted through the slot 92 as above described.

It should also be understood that at the completion of a winding operation the vertical component 81 may come to rest in a downwardly extending position with reference to the lower reach 41z, as shown in dot-and-dash lines at the right in Fig. 1a. In this event it is necessary to first swing the device 29t about the axis of the lower reach 41z to the upwardly extending full line position above the reach 41z. The device 29t may then be swung upper end leftwardly in Fig. 1a until the slots 91 and 92 are substantially parallel with the line so that the reaches 41w and 41x, 41y may be inserted through the slots.

A modified form of holder, 29s, is constructed for use on the two reach clothes line 41 shown in Figs. 1 and 6. It also includes a horizontal component 80s and a vertical component 81s, the horizontal component having a winding device 31s and a holding means 45s like those of the holder 29r. The component 81s has a slot 86x' with which a diagonally extending slot 86y communicates and through which the upper reach 40' may be passed to a roller 86 in the slot 86x', said roller being provided to facilitate transit of the holder on the upper reach 40'.

It will be understood that the holding device 45r of the device 29r, Fig. 7, in addition to preventing reverse rotation of the winding device 31r, while in engagement with the clothes carrying reach, is also effective to prevent rotation of said device about an axis which is substantially in alignment with the axis of the vertical component 81 and thus prevent binding of said component on the reaches 41w, 41x and 41y. This tendency to so rotate the holder 29r is caused by the sections of the reach 41z at opposite sides of the component 81 because they lie in adjacent vertical planes and produce the effect of a couple. Similarly the holding means 45s, Fig. 6, prevents rotation of the holder 39s about its vertical axis to prevent binding of the component 81s on the reach 40'.

The type of holder illustrated in Figs. 6 and 7 may also be applied to the clothes carrying reach of the line without winding up a portion of the reach on the winding device in the event that the line is tight enough. How this is accomplished will now be described in connection with the holder 29r of Fig. 7. The clothes carrying reach 41z may first be caused to lie on the top face of that portion of the winding device to the left of the slot 33r, Figs. 7 and 9, it may

then be extended through the slot 33r, then around the lower face of that portion of the winding device to the right of the slot and is finally passed over the extension of the holding means 45s. Thus it will be understood that under this condition the winding device 31s and the holding means 45s cooperate to form a bight in the reach 41z which grips the holder to cause it to travel with said reach, and also cause the holder to extend perpendicular to the reaches of the line to prevent accidental passage of the reaches through the diagonal slots 91 and 92 in Fig. 7 and 86y in Fig. 6.

While certain preferred embodiments of the invention have been described, it will be understood that certain parts may be used with others and that changes in the form, arrangement, proportions, size and details thereof may be made without departing from the scope of the invention as defined in the appended claims.

I claim:

1. The combination with a pulley clothes line having two reaches, of a device to act on one of said reaches to tighten the line, an arm on said device which arm may be rotated in a plane parallel to a plane in which the reaches of the clothes line are disposed to rotate said device and thus tighten the line, means on said arm to engage the other reach of the clothes line to maintain said reaches in close proximity, and means to prevent accidental reverse rotation of said arm in the plane in which said reaches are disposed.

2. The combination with a line, of a device 35 to tighten or slacken said line, said device comprising two members disposed substantially at right angles to each other, one of said members constituting a winding device upon which a portion of the line may be wound, the other member 40 constituting a handle by which the first mentioned member may be actuated, said line having two reaches, said device being supported on one of said reaches, and a roller on the handle member to engage the other reach of said line.

45 3. The combination with a line, of a device to tighten or slacken said line, said device comprising two members disposed substantially at right angles to each other, one of said members constituting a winding device upon which a portion of the line may be wound, the other member 50 constituting a handle by which the first mentioned member may be actuated, said line having four reaches, namely a lower reach, an upper reach to travel in the same direction as the lower reach, and two intermediate reaches to travel in a direction opposite to the upper and lower reaches, said device being supported on the lower reach, said handle member extending upwardly from the lower reach to embrace the upper reach and 55 the intermediate reaches.

60 4. In a line tightener, the combination of a lever, a winding device at one end thereof upon which a portion of one reach of a pulley line may be wound by actuating said lever about 65 the axis of said winding device, said lever being disposed with reference to the winding device so that it may be actuated by rotating said lever about its longitudinal axis so as to carry said winding device bodily about the axis of said lever 70 to thus unwind the line from the winding device, means on said lever to engage and ride on another reach of said line to keep said reaches close to one another, and means to maintain said lever in a position vertical to the reaches of the pulley 75 line.

5. In a line tightener for a pulley clothes line having two reaches disposed in the same plane, the combination of winding means to engage one of said reaches and rotatable about its axis to wind up a portion of one reach thereon, a lever to rotate said winding means, means on said lever to engage the other reach of the line to maintain the reaches spaced close to each other, and means on said tightener to engage the first mentioned reach to prevent accidental rotation of the tightener about the axis of its lever to thus prevent binding of the second mentioned means on the reach which it engages.

6. In a line tightener for a pulley clothes line having two reaches disposed in the same plane, the combination of winding means to engage one of said reaches and rotatable about its axis to wind up a portion of the reach, a lever on and effective to rotate said winding means, means on said tightener to prevent reverse rotation of the winding means, and means on said lever to engage the other reach of the line to retain the reaches definitely spaced with respect to each other, the reverse rotation preventing means being also effective to prevent accidental rotation of the tightener about the axis of its lever to thus prevent the means which engages said other reach from binding against the latter.

7. In a line tightener for a pulley clothes line having two reaches disposed in the same plane, the combination of winding means to engage one of said reaches and rotatable about its axis to wind up a portion of the reach, a lever to rotate said winding means, said lever having a slot into which the other reach of the line may be inserted, a roller in said slot to bear on the upper side of said other reach to maintain the reaches in closely spaced relation, and means rigid on said lever to prevent reverse rotation of the tightener to prevent accidental unwinding of the line therefrom, the last mentioned means being also effective to prevent accidental rotation of the tightener about the axis of its lever and thus prevent binding of the lever through the medium of its slot on said other reach.

8. In a tightener for a pulley clothes line having two outer reaches, and an intermediate reach, the combination of winding means to engage one of the outer reaches, a lever to actuate said winding device, means on said lever to engage the intermediate reach to keep it closely spaced relatively to the outer reach which is engaged by the winding means, means on said lever to engage the other outer reach to keep it closely spaced to the intermediate reach, and means rigid on said lever to prevent accidental rotation of the tightener about the axis of its lever and thus prevent binding of said lever on the intermediate reach and said other outer reach.

9. In a tightener for a pulley clothes line having two outer reaches, and an intermediate reach, the combination of winding means to engage one of the outer reaches, a lever to actuate said winding device, said lever having two slots therein, one into which the intermediate reach may be inserted, the other into which the other outer reach may be inserted, and means rigid on said lever to prevent accidental rotation of the tightener about the axis of said lever to thus prevent binding of said lever on the reaches in said slots.

10. A line tightener, having in combination, a lever with flat oppositely disposed faces, a winding device rigid on said lever and located at one

side and at one end thereof, said winding device having an axis about which it may be rotated in either direction by said lever to wind up a portion of said line thereon, said winding device being of the same thickness as that end of the lever at which it is located, an extension at the opposite end and the same side of said lever, said extension being of the same thickness as that end of said lever where it is located, said extension having opposite faces flush with the opposite faces of said lever, said extension having two grooves one in each face thereof, said grooves extending towards the winding device, both grooves being diagonally disposed with reference to the faces of said extension and diverging from each other so that the ends farthest from the winding device merge with the flat faces of said extension, the line being insertable into either one of said grooves depending upon the direction in which the winding device has been rotated to wind the line thereon, and a tongue on said extension projecting beyond the ends of both grooves and towards the winding device.

11. In a clothes line holder, the combination of means to grip and support the clothes carrying reach of a clothes line, means to engage an idle reach of the clothes line to permit freedom of transit of the holder on the idle reach, and relatively fixed means to prevent accidental detachment of the holder from the idle reach, the relatively fixed means permitting the free passage of the idle reach from the holder only when the latter is disposed diagonally with respect to a portion of the idle reach and without disturbing said relatively fixed means, the gripping means being effective to maintain the holder perpendicular to the idle reach and thus cause the relatively fixed means to function.

12. In a clothes line holder, the combination of means to attach the holder to the clothes carrying reach of a pulley clothes line to cause the holder to travel with said reach, said means being also effective to maintain said holder vertical to the pulley line, a roller to engage an idle reach of the clothes line, a fixed member on said holder to be located under the idle reach of the line, and stationary means on said holder to cooperate with said fixed member to prevent accidental detachment of the idle reach from the holder when the holder is perpendicular to the idle reach, said fixed member and said stationary means being disposed with respect to one another to permit removal of the idle reach from the holder only when said holder is tilted to a position diagonal to a portion of the idle reach.

13. In a clothes line holder, the combination of means to attach the holder to the clothes carrying reach of a pulley clothes line to cause the holder to travel with said reach, said means being also effective to maintain said holder vertical to the pulley line a roller to engage an idle reach of the clothes line, means to limit the extent of movement of the idle reach away from the roller, and means extending beyond the line engaging portion of said roller to cooperate with the limiting means and thereby prevent accidental detachment of the holder from the idle reach while the holder is perpendicular to said idle reach, the extending means and limiting means being positioned with respect to each other to form a slot diagonally disposed with reference to the idle reach so that the idle reach may be passed freely through said slot only when the holder is placed diagonally with reference to

a portion of said idle reach so as to position said slot substantially parallel to the idle reach.

14. The combination with a pulley clothes line having two reaches, of a holder to keep said reaches spaced close to one another, said holder having a single body part, means on said body part to engage one reach of the clothes line and permit freedom of transit of said holder on said reach, and means on said body part to form a bight in the other reach of the clothes line to thereby grip and thus cause the latter to travel with the last mentioned reach of the clothes line, said last mentioned means being located at one side of said body part so that the clothes line reach may readily be inserted into the bight forming means entirely from one side in full view of the operator.

15. The combination with a pulley clothes line having a lower reach and an upper reach of a holder including means to grip the lower reach to cause the holder to travel therewith, a member extending upwardly from the gripping means to engage the upper reach to maintain the reaches in close proximity, said member having a slot to accommodate the upper reach, and means forming a slot diagonally disposed with reference to the upwardly extending member and extending from the exterior of said holder into the reach accommodating slot, the gripping means when on the reach which it engages being effective to maintain the upwardly extending member in a vertical position, said diagonally disposed slot being slightly wider than the thickness of the upper reach so that the latter may be passed freely through said diagonally disposed slot to or from the reach accommodating slot when the holder is tilted, against the combined action of the gripping means and the reach it engages, to a position in which the diagonal slot is substantially parallel to the upper reach.

16. The combination with a pulley clothes line having three reaches, namely two outer reaches, and an intermediate reach, of a holder including means to grip one of the outer reaches to cause the holder to travel therewith, a member extending from the gripping means and transversely of the intermediate reach and the other outer reach to maintain all of the reaches definitely spaced from each other, said member having two reach accommodating slots, one for the intermediate reach, and one for said other outer reach, and means forming two diagonally disposed slots, each reach accommodating slot having one of the diagonally disposed slots communicating therewith, the gripping means being

effective, when on its associated reach, to maintain said member in its transverse position to prevent accidental removal of the upper reach and the intermediate reach from the reach accommodating slots, each diagonally disposed slot being slightly wider than the thickness of the line reaches so that the respective reaches may be passed freely through the diagonal slots from or to their reach accommodating slots after the holder has been tilted to move said member from its transverse position, against the combined action of the gripping device and its associated reach, to bring the diagonal slots to positions substantially parallel with said reaches.

15 17. The combination with a pulley clothes line having a plurality of reaches, of rotatable means to act on one of said reaches to wind up a portion of said reach thereon to thus tighten the line, and a handle to actuate the rotatable means, said 20 handle to engage the other reach of said line to maintain both reaches closely spaced with respect to each other.

18. The combination with a pulley clothes line having a plurality of reaches, of a rotatable device to act on one reach of the line to wind up a portion of said reach thereon to thus tighten the line, a handle rigid on the rotatable device by which said device may be operated, the line tending to reversely rotate said rotatable device 30 while a portion of the reach is wound thereon, means to engage one of said reaches to prevent accidental reverse rotation of said rotatable device, and means on said handle to engage another one of said reaches to maintain both reaches 35 closely spaced with respect to each other.

19. The combination with a pulley clothes line having a plurality of reaches, of a rotatable device to act on one reach to wind up a portion of said reach thereon to thus tighten the line, a body 40 part on which said device is rigidly supported and whereby the rotatable device may be actuated, a roller on said body part which may be caused to engage another one of said reaches to maintain both reaches close to each other, the 45 line tending to reversely rotate said rotatable device while a portion of the reach is wound thereon, means to hold said device against reverse rotation and to hold said body part substantially perpendicular to said line, and a member on 50 said body part which is effective to prevent accidental disengagement of said roller from its cooperative reach while the body part is held substantially perpendicular to said reaches.
